TUBE SEAL

Filed Feb. 10, 1930

INVENTOR.

By Alfred W. Kath
Francis D. Hardesty

ATTORNEY.

UNITED STATES PATENT OFFICE

ALFRED W. KATH, OF DETROIT, MICHIGAN, ASSIGNOR TO ARTHUR COLTON COMPANY,
OF DETROIT, MICHIGAN, A CORPORATION OF MICHIGAN

TUBE SEAL

Application filed February 10, 1930. Serial No. 427,130.

The present invention relates to collapsible tube containers and more especially to the closing of such tubes after filling. Tubes of this type are used for many purposes and because of this the resulting production is a great many millions annually. A small saving, therefore, in connection with each tube represents in the aggregate a considerable sum.

10 Heretofore, it has been the customary and substantially the universal practice to fold over the collapsed end of the tube, after filling, and then to place over the fold a V-shaped clip of comparatively stiff metal, which is then squeezed together over the fold.

15 Among the objects of the present invention is to do away with the use of such clips and securely close the end of the tube utilizing only the metal of the tube itself.

20 Another object is to provide a tube having a closing seam composed only of the tube metal and presenting a neat appearance, besides offering considerable resistance to being opened due to squeezing.

25 Another object is a tube closure of the kind indicated which permits the tube to be tightly rolled as the contents are removed.

Other objects will readily occur to those skilled in the art upon reference to the following description and the accompanying drawings in which

Fig. 1 is a view in elevation of a closed tube embodying the invention.

Fig. 2 is a section on line 2—2 of Fig. 1.

30 Fig. 3 is an enlarged view of the section shown in Fig. 2.

Fig. 4 is a similarly enlarged section showing an intermediate step in the closing.

Fig. 5 shows a modified form of the seal.

35 In the drawings a collapsible tube containing the commodity is indicated at 10 with the screw cap at 11 and the sealed end at 12. As stated above, the usual method of sealing is to fold over the collapsed end and apply thereto a metal clip of relatively stiff metal.

40 In the present case, the tube may be filled in the usual manner and the end collapsed, but instead of folding once and applying a clip, the collapsed tube is folded over two or more times in the same direction as indi-

cated at 20 in Fig. 4. After this is done, the several thicknesses of metal are folded back the other way on a line 21 substantially half way between the edges of the double fold 20 as indicated by the dotted lines in Fig. 4 and by Fig. 3, the latter showing the finished fold or seal in section.

This procedure provides on one side of the tube walls 22, four thicknesses of metal and, on the other, six as illustrated in Fig. 3; producing a stiff folded end which in itself is at least four times as stiff as the tube wall, thus effectively preventing blowing out of the contents.

If desired, the folding may be done by means of suitable dies to produce a finished appearance with sharp corners as shown, if this should be found desirable. Or, the fold may be corrugated as shown at 12a in Fig. 5 to increase the stiffness.

Now having described the invention and the preferred embodiment thereof, it is to be understood that the said invention is to be limited, not to the specific details herein set forth, but only by the scope of the claims which follow:

Claims:—

1. A collapsible tube sealed by loop folding in a direction away from one side of the tube the ends of the collapsed walls, and then folding back in a direction away from the other side of the tube the fold thus produced, said folding back being on a line at substantially the middle of the first loop fold, the sealing folds extending completely transversely of the tube.

2. A collapsible tube sealed by loop folding the ends of the collapsed walls a plurality of times to form a loop fold on one side of the tube and then folding back against the other side of the tube the loop fold thus produced, said folding back being on a line at substantially the middle of the first loop fold, the sealing folds extending completely transversely of the tube.

3. A collapsible tube sealed by loop folding in a direction away from one side of the tube the ends of the collapsed walls and then folding back in a direction away from the other side of the tube the fold thus produced,

said folding back being on a line at substantially the middle of the first loop fold, and corrugating said folds to form ribs and grooves extending lengthwise of the tube,
5 the sealing folds extending completely transversely of the tube.

4. A collapsible tube sealed by loop folding the ends of the collapsed walls a plurality of times to form a loop fold on one side of
10 the tube and then folding back against the other side of the tube the loop fold thus produced, said folding back being on a line at substantially the middle of the first loop fold, and corrugating said folds to form ribs and
15 grooves extending lengthwise of the tube, the sealing folds extending completely transversely of the tube.

5. The method of sealing the end of a collapsible tube which consists in loop-folding
20 in a direction away from one side of the tube, the full length of the ends of the collapsed walls, then folding back, in a direction away from the other side of the tube the full length of the loop fold thus produced, on a line at
25 substantially the middle of the first loop fold.

6. The method of sealing the end of a collapsible tube which consists in loop folding the full length of the ends of the collapsed walls against one side of the tube, then folding
30 back against the other side of the tube the full length of the loop fold thus produced on a line at substantially the middle of the first loop fold.

7. The method of sealing the end of a collapsible tube which consists in loop-folding
35 in a direction away from one side of the tube, the full length of the ends of the collapsed walls, then folding back, in a direction away from the other side of the tube
40 the full length of the loop fold thus produced, on a line at substantially the middle of the first loop fold, and corrugating said folds to form ribs and grooves extending lengthwise of the tube.

45 8. The method of sealing the end of a collapsible tube which consists in loop folding the full length of the ends of the collapsed walls against one side of the tube, then folding back against the other side of the tube
50 the full length of the loop fold thus produced on a line at substantially the middle of the first loop fold, and corrugating said folds to form ribs and grooves extending lengthwise of the tube.

55 ALFRED W. KATH.
